CLAIM

The ornamental design for a personal air purifier, as shown and described.

DESCRIPTION

FIG. 1 is a top front perspective view of a personal air purifier showing my new design;

FIG. 2 is a bottom rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a top front perspective view thereof, wherein the personal air purifier is shown with an adjustable outlet vent;

FIG. 10 is a reduced front view thereof, wherein the personal air purifier is shown with an air nozzle; and,

FIG. 11 is a reduced front view thereof, wherein the personal air purifier is shown with a face mask.

The broken lines showing an outlet attachment in FIGS. 1-7, the broken lines showing an air fan in FIGS. 1 and 9, the broken lines showing an adjustable outlet vent in FIG. 9, the broken lines showing an air nozzle and tubing in FIG. 10, and the broken lines showing a face mask and tubing in FIG. 11 are included for the purpose of illustrating environmental structure and form no part of the claimed design.
